UNITED STATES PATENT OFFICE.

EDWARD H. ST. CLAIR, OF PARIS STATION, CANADA.

DETACHABLE-TOOTH COMB.

1,322,268.

Specification of Letters Patent.

Patented Nov. 18, 1919.

Application filed February 23, 1918, Serial No. 218,367. Renewed August 28, 1919. Serial No. 320,439.

To all whom it may concern:

Be it known that I, EDWARD H. ST. CLAIR, residing at Paris Station, in the Province of Ontario and Dominion of Canada, have invented certain new and useful Improvements in Detachable-Tooth Combs, of which the following is a specification.

This invention relates generally to combs, and particularly combs constructed in such manner as to permit of the teeth being detached from the body portion for the purpose of cleaning or repair.

The primary object of the invention is to provide a comb of that type which includes a body portion and removable teeth, wherein the construction is such as to permit of the teeth being readily removed from the body and assembled therewith, and wherein there is provided improved means for holding the teeth rigid with the said body portion.

A further object of the invention is to provide a comb of the character mentioned which is constructed in such manner as to at all times maintain the teeth in proper alignment and spaced apart the required distance, which may be constructed or produced at low cost, which comprises but very few simple and readily assembled parts, which has its various parts so assembled as to minimize the opportunity for breakage either of the body or teeth, and which will prove thoroughly practical and efficient in use.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

Figure 1 is an elevation, parts broken away, of a comb constructed in accordance with the invention,

Fig. 2 is a transverse sectional view on an enlarged scale taken substantially upon line 2—2 of Fig. 1,

Fig. 3 is a view similar to Fig. 2 and showing a slightly modified form of the invention,

Fig. 4 is a view similar to Fig. 2 and showing a further modified form of the invention, and

Fig. 5 is a similar view showing a still further modified form of the invention.

Referring now more particularly to the drawings, 6 represents the body portion of the improved comb, and to which are detachably secured the teeth 7. The body 6 in the preferred embodiment of the invention comprises an elongated tubular member as shown, having one end closed permanently by a head 8 and the other end closed by the removable cap 9. This cap has projecting inwardly from the center thereof a rod 10 which is adapted at its free end to engage in a suitable opening in the head 8. The teeth 7 in this form of the invention are provided at their inner ends with apertures 11 to receive the rod 10, and it will be understood that the apertures will be disposed in the teeth 7 at such points that the free ends of the teeth will be properly aligned. The body or tubular member 6 is provided with a longitudinal series of spaced apertures 75 through which the teeth 7 project, and it is preferred that these apertures be of such size as to snugly accommodate the comb teeth.

In Fig. 3 of the drawings there is shown a slightly modified form of the invention, and wherein the rod 10 is arranged eccentrically within the tubular member, and is adapted to engage in notches 12 in the edges of the teeth 7. In other respects the structure is similar to that shown in the preferred embodiment.

In Fig. 5 of the drawings there is a further modification of the invention, and wherein the rod 10 is cut away so as to provide an angular edge adapted to engage within the notch 13 in the comb tooth 7, the latter having a sharp shoulder as shown to be engaged by the angular edge of the rod 10.

In Fig. 4 of the drawings there is shown a still further modification of the invention, and wherein the longitudinal series of openings in the body have their edges threaded to receive the threaded ends 14 of the teeth 7. In this form of the invention, the upper ends of the teeth will be rounded, and the rounded portions will be threaded to engage within the threaded apertures in the body 6.

From the foregoing it is obvious that I have provided a comb which is of extremely simple construction and which may be readily cleaned or repaired when required. When it is desired to remove the teeth of 110

the device shown in the preferred embodiment of the invention, it is but necessary to unscrew the cap 9 and withdraw the rod 10 from the interior of the tube, and the teeth 5 7 may be easily withdrawn from the said body. After the teeth have been cleaned or repaired, they may be readjusted to the body and by inserting the rod 10 in the openings in the various teeth, the latter will be locked 10 securely in proper position. The operation of the devices shown in Figs. 3 and 5 are similar, and in the device shown in Fig. 4, the various teeth are separately removable.

It is obvious that by the use of a comb of 15 this character the same may be at all times kept in a sanitary condition, and should any of the teeth become broken or distorted they may be easily replaced by new teeth.

While the present is a disclosure of what 20 is believed to be the preferred embodiment of the invention, it is to be understood that the invention is not limited thereto, as various changes in the minor details of construction, proportion, and arrangement of parts 25 may be resorted to if desired without departing from the spirit of the invention as defined by the appended claims.

I claim:—

1. In a comb, a tubular body, the said 30 body being provided with a plurality of spaced apertures, teeth having their inner ends engaged in said apertures, each of said teeth being provided at its inner end with an annular notch, a screw cap closing one 35 end of said body, and a rod projecting inwardly from said screw cap and adapted

to be engaged in the notches in the inner ends of said teeth.

2. In a comb, a tubular body, a head closing one end of said body and being provided with an opening, the said body being provided with a plurality of spaced apertures, comb teeth seated in said apertures, each tooth having a groove, a screw cap closing the opposite end of said body, a rod secured 40 to said screw cap and resting at its free end in the opening in said head, and the said rod adapted to be engaged in the notches in the teeth.

3. In a comb, a body having apertures 50 therein, a rod extending centrally through said body, teeth projecting through said apertures, the said teeth being provided at their inner ends with notches, and the said rod being engaged in said notches.

4. A comb including a tubular body having a series of spaced apertures therein, said apertures being alined longitudinally of said tubular member, comb teeth seated in said apertures and each of said teeth having an 60 annular groove near the inner end thereof, a screw cap closing one end of said tubular member, and a rod secured to said screw cap and extending centrally into said tubular member and engaged in the notches in 65 the inner ends of said teeth.

In testimony whereof I affix my signature in presence of two witnesses.

EDWARD H. ST. CLAIR.
